OIL CAN

Ralph V. Jenkins, Salt Lake City, Utah

Application April 1, 1940, Serial No. 327,314

4 Claims. (Cl. 221—32)

The invention relates to a dispensing can and more especially to oil cans.

The primary object of the invention is the provision of a can of this character wherein the spout thereof is concealed and closed so as to eliminate leakage of oil or other liquid from the can when the same is out of position for use and such spout can be exposed and the contents of the can dispensed therethrough in a ready and convenient manner.

Another object of the invention is the provision of a can of this character wherein its construction is novel in its entirety and will assure against waste of oil or liquid as contained within the body of the can when the latter is stored or not in use and such can can be readily manipulated for use particularly for oiling purposes.

A further object of the invention is the provision of a can of this character wherein the receptacle for the oil having the discharge spout is confined within a holder which fully protects such receptacle and spout to avoid damaging the same when stored or at rest upon a support when not in use and the oil within the receptacle is readily dispersed through the spout on the projecting thereof from the holder.

A still further object of the invention is the provision of a can of this character, which is simple in its construction, thoroughly reliable and efficient in operation, the oil content being free from contamination and is readily dispensable with dispatch, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claims hereunto appended.

In the accompanying drawing:

Figure 1 is a perspective view of the can constructed in accordance with the invention and in position for oiling purposes.

45 Figure 2 is a sectional view taken on the line
2-2 of Figure 3 looking in the direction of the
arrows and showing by full lines an adjusted
position and by dotted lines another adjusted
position thereof.

50 Figure 3 is a top plan view.

Figure 4 is a sectional view taken on the line 4-4 of Figure 2 looking in the direction of the arrows.

55 Similar reference characters indicate corre-

sponding parts throughout the several views in the drawing.

Referring to the drawing in detail, A designates generally an oil can proper which comprises a cylindrical receptacle 5 sealed at its top and bottom and from the top eccentrically to the longitudinal center thereof is an outwardly disposed dispensing spout 6, being united with the body or receptacle 5 in any suitable manner while adapted to be sealed within the body or receptacle 5 is a quantity of oil to be dispensed or discharged through the spout 6 on compressing the said receptacle or body through exterior force against the same, being usually applied by the fingers of a hand of the user of the can.

This body or receptacle 5 is slidably fitted within an elongated cylindrical holder 7, its length being considerably greater than the length of the receptacle or body 5, which is also elongated. One end of the cylindrical holder 7 is permanently closed by a bottom or cap 8 while the other or opposite end of such holder 7, being opened, is formed with an external annular bead edge 9 for separable fastening of a cover or cap 10 which marginally thereof is formed with springy latching lips or tongues 11 adapted to be brought into latching engagement with the bead edge and in this manner separably fastening the cover or cap 10 upon the holder 7. 20 25

The cover or cap 10 has struck outwardly from 30 the inner side thereof concentric to its center an arcuate-shaped channel or groove 12 receptive to the tip or end of the spout 6. The channel or groove 11 merges into an opening or hole 13, which is at one end of the latter, and through 35 which is adapted to be projected the spout 6 for the discharge of the contents of the body or receptacle 5 through said spout when the can is used for oiling purposes. The other end of the groove or channel 11 opens into a cork lined seat 40 14 for the free end of the spout 6 and such seat is deeper than the channel or groove so that the spout 6 when engaged at its free end within the seat will not accidentally work into the channel or groove 11 until the body or receptacle 5 is 45 manually manipulated for this purpose. The lining to the seat 14 will seal the tip or end of the spout 6 when engaged in said seat as will be apparent from Figure 2 of the drawing.

Located between the bottom or cap 8 and the end adjacent thereto of the body or receptacle 5 is a coiled tensioning spring 15 which functions to urge the said body or receptacle 5 in the direction of the cover or cap 10 and also to effect the passage of the spout 6 through the hole or opening 55.

ing 13 when such spout is aligned therewith. This exposure of the spout 6 places it in a position so that the application of oil can be had as the occasion may require.

- 5 At diametrically opposite sides of the holder 7 are windows or finger-receiving apertures 16 so that the receptacle or body 5 can be engaged to permit of the turning thereof within the holder 7 to bring the spout 6 aligned with the opening 10 or hole 13 or for the shifting of such spout to have its free end engaged in the seat 14. These windows or apertures 16 also permit of compressing the receptacle or body 5 for forcing of oil therefrom through the spout to dispense such oil.
- 15 The holder 7 next to the apertures or windows 16 has inwardly struck therefrom friction lugs 17 for engaging the receptacle or body 5 and effecting keepers to maintain the said body or receptacle 5 against free sliding movement within the holder 7 and also to assure steadiness in the projection of the spout 6 through the opening or hole 13.

From the foregoing it is thought that the construction and manner of operation of the device 20 will be clearly understood and therefore a more extended explanation has been omitted.

What is claimed is:

1. An oil can comprising a body proper for holding oil and having a spout projecting from one end thereof, a cylindrical holder slidably receiving the said body and having a finger-admitting opening for the engagement of the said body when within the cylindrical holder means within the holder for urging the body in the direction of one end of said holder, and a cap releasably fitting the holder and having a runway for the spout and also provided with a clearance for the projecting of the spout therethrough.
- 30 2. An oil can comprising a body proper for holding oil and having a spout projecting from one end thereof, a cylindrical holder slidably receiving the said body and having a finger-admitting opening for the engagement of the said body when within the cylindrical holder, means within the holder for urging the body in the direction of one end of said holder, a cap releasably fitting the holder and having a runway for the spout and also provided with a clearance for the projecting of the spout therethrough, the said runway being formed with a seat, a sealing medium confined within the seat for the sealing of the spout when engaged within the seat, and friction projections formed with the holder for engaging the body and maintaining the spout projected through the cap.
- 35 3. An oil can comprising a body proper for holding oil and having a spout projecting from one end thereof, a cylindrical holder slidably receiving the said body and having a finger-admitting opening for the engagement of the said body when within the cylindrical holder, means within the holder for urging the body in the direction of one end of said holder, a cap releasably fitting the holder and having a runway for the spout and also provided with a clearance for the projecting of the spout therethrough, the said runway being formed with a seat, a sealing medium confined within the seat for the sealing of the spout when engaged within the seat, and friction projections formed with the holder for engaging the body and maintaining the spout projected through the cap.
- 40 4. An oil can comprising a body proper for holding oil and having a spout projecting from one end thereof, a cylindrical holder slidably receiving the said body and having a finger-admitting opening for the engagement of the said body when within the cylindrical holder, means within the holder for urging the body in the direction of one end of said holder, a cap releasably fitting the holder and having a runway for the spout and also provided with a clearance for the projecting of the spout therethrough, the said runway being formed with a seat, a sealing medium confined within the seat for the sealing of the spout when engaged within the seat, and friction projections formed with the holder for engaging the body and maintaining the spout projected through the cap, and springy lips formed on the cap for releasably latching it to the holder.

within the holder for urging the body in the direction of one end of said holder, a cap releasably fitting the holder and having a runway for the spout and also provided with a clearance for the projecting of the spout therethrough, the said runway being formed with a seat, and a sealing medium confined within the seat for the sealing of the spout when engaged within the seat.

3. An oil can comprising a body proper for holding oil and having a spout projecting from one end thereof, a cylindrical holder slidably receiving the said body and having a finger-admitting opening for the engagement of the said body when within the cylindrical holder, means within the holder for urging the body in the direction of one end of said holder, a cap releasably fitting the holder and having a runway for the spout and also provided with a clearance for the projecting of the spout therethrough, the said runway being formed with a seat, a sealing medium confined within the seat for the sealing of the spout when engaged within the seat, and friction projections formed with the holder for engaging the body and maintaining the spout projected through the cap.

4. An oil can comprising a body proper for holding oil and having a spout projecting from one end thereof, a cylindrical holder slidably receiving the said body and having a finger-admitting opening for the engagement of the said body when within the cylindrical holder, means within the holder for urging the body in the direction of one end of said holder, a cap releasably fitting the holder and having a runway for the spout and also provided with a clearance for the projecting of the spout therethrough, the said runway being formed with a seat, a sealing medium confined within the seat for the sealing of the spout when engaged within the seat, and friction projections formed with the holder for engaging the body and maintaining the spout projected through the cap, and springy lips formed on the cap for releasably latching it to the holder.

RALPH V. JENKINS. 45
